FIG. 1

FIG. 2

FIG. 3

FIG. 4

FIG. 5

FIG. 6

FIG. 7

FIG. 1 is a perspective view of a combined recording and reproducing machine or similar article showing the front, top and left end of my new design;

FIG. 2 is a perspective view showing the back, top and right end;

FIG. 3 is a top plan view to a reduced scale;

FIG. 4 is a front elevational view to a reduced scale;

FIG. 5 is a right end elevational view, to a reduced scale;

FIG. 6 is a rear elevational view thereof, to a reduced scale; and

FIG. 7 is a left hand elevational view, to a reduced scale.

In FIGS. 3, 4 and 5 the microphone hook has been depicted in retracted position for convenience in illustration.

This is a continuation-in-part of application Serial No. D. 77,698, filed December 6, 1963, now abandoned.

I claim:

The ornamental design for a combined recording and reproducing machine or similar article, as shown and described.
